DES. 2162

Rudolph Wendt of New York, N.Y.

Letters Patent No. 2162-Dated Aug. 8, 1865.

Design for a Spoon Handle.

The schedule referred to in these Letters Patent and making part of the same.

shall whom it may concern:

Be it known that I, Rudolph Wendt of the City, County, and State of New York, have invented a ornamental design for Spoon Handles, and I do hereby declare that the following is a full, clear and exact description thereof which will enable those skilled in the art to make and use the same, reference being had to the accompanying drawing forming part of this specification, in which,

Figure 1, represents a plan of the upper surface of my spoon handle.

Figure 2, is a plan of the lower surface.

Similar letters of reference indicate like parts.

This design consists of an oval enclosed by double borders. The upper extreme end of the oval is ornamented by small arabesque and the lower pointed end of the same extends under the double border of the circular field, and terminates in a small arabesque. The double border of the circular space continues down on the sides of a groove in the hand of the handle and they join in an arabesque near the junction of the handle with the bowl. The outer border of the circular space continues and forms two circles one inside the

other, in the lower part of the oval.

A represents a handle, the upper portion of which forms an oval a. This oval is provided with a double border, and its outer end is ornamented by a small arabesque.

The inner pointed end of the oval extends under the double border of the circular space, and it terminates in an arabesque f.

The double border of the circular space extends down on the side of semicircular groove g, and it terminates near the junction of the handle with the bowl in an arabesque.

The outer border of the circular space extends and forms two circles, one inside the other in the oval.

The ornament on the under surface of the handle are substantially the same with the addition of an escutcheon ornamented with suitable arabesques which covers the junction of the handle with the bowl.

Claim as now and desire to secure by letters Patent.

The design for a spoon handle as herein shown and described.
